T. N. SMITH.
SAND DRIER.
APPLICATION FILED JUNE 3, 1912.

Patented Oct. 15, 1912.

UNITED STATES PATENT OFFICE.

THOMAS N. SMITH, OF PORTSMOUTH, VIRGINIA.

SAND-DRIER.

1,041,523.

Specification of Letters Patent. Patented Oct. 15, 1912.

Application filed June 3, 1912. Serial No. 701,845.

To all whom it may concern:

Be it known that I, THOMAS N. SMITH, a citizen of the United States, and a resident of Portsmouth, in the county of Norfolk and State of Virginia, have invented a certain new and useful Sand-Drier, of which the following is a specification.

This invention relates to sand driers of the general type set forth in my co-pending application, Ser. No. 637,246, and aims to simplify and otherwise improve the construction and operation of apparatus of this type.

Other objects, as well as the nature, characteristic features, and scope of the invention will more readily be understood from the following description taken in connection with the accompanying drawing, forming a part hereof, wherein,

Figure 1, is a central vertical section of a sand drier embodying my invention. Figs. 2 and 3, are sectional details, the one showing the cleaning doors, and the other showing the angle irons or distance pieces which sustain the outer wall of the sand basket.

Referring to the drawing, *a*, represents a suitable heater; *b*, represents a superstructure involving a wet sand basket or holder and a heat deflector; and *c*, represents a stack.

The heater or furnace *a*, is equipped with a suitable grate 1, an ash pit 2, and with fuel and ash doors 3, and 4. That part of the furnace casing forming the hot air chamber is somewhat flaring and has mounted upon it a ring or annulus 5, that supports in turn the heat deflector, sand basket or holder, and outer shell or casing 6. Said shell or casing 6, is an imperforate member and is equipped near its base with vertically sliding doors 7; which afford ready access for cleaning purposes, and at its top with a door 8, through which the wet sand is introduced. A cable 9, made fast to door 8, and running over pulleys 10, affords a convenient means of raising and lowering said door.

The basket or holder for the wet sand is constituted of two screens 11, and 12, whereof the outer screen 12, is supported by bridges 13, on the ring 5, and by angle irons 14, which constitute distance pieces for holding the screen and shell apart, and form a passage 15, intermediate the two for hot air, which eventually finds its way into the stack through orifices 16. This is mani-

festly advantageous, in that the wet sand is kept out of contact with the shell, thus prolonging the life of the latter, and, also, in that a quicker drying is effected through the greatly increased drying area. The inner or bottom screen 11, extends from the ring or annulus 5, to a sleeve 17, which telescopes the stack. The stack is provided with a bolt or pin 18, and the sleeve 17, has a slot 18', so that in the event of repairs the sleeve may be elevated and maintained in raised position by causing the bolt 18, to engage the slot 18'. The stack is sustained by a guide 19, and its downward movement is limited by a collar 20.

The described arrangement of the inner wall or screen of the basket provides an axial flue or passage 21, that connects the stack and heater. Mounted in said axial passage is a heat deflector consisting of a hollow cone 22, the depending wall or skirt of which is supported by bridges 23, seated on the inwardly directed offset 24, of the annulus 5. Obviously the spaces between the bridges constitute passages 25, for hot air and also for the dry sand.

The heat deflector is provided with a damper 26, that can be operated from the outside by a damper rod 27. Below the deflector and the flues or passages 25, is a sand catcher or receptacle 28, supported as at 29, and provided with a discharge chute 30, leading out of the furnace.

It will be obvious to those skilled in the art to which the invention relates that modifications may be made in details without departing from the spirit and scope of the invention. Hence the same is not limited other than required by the prior state of the art.

Having described the nature and objects of the invention, what I claim and desire to secure by Letters Patent is:—

1. The combination of a heater, its stack, a sand basket, having an axial space or passage connecting the heater and stack, and a shell or casing inclosing the basket and forming a surrounding hot air passage.
2. The combination of a heater, its stack, a perforate sand basket having an axial space or passage that connects the heater and stack, and an imperforate shell or casing inclosing the basket and forming therewith a surrounding hot air passage.
3. The combination of a heater, its stack, a perforate sand basket having an axial

- space or passage that connects the heater and stack, a shell or casing inclosing the basket and forming therewith a surrounding hot air passage, and a receptacle for 5 dry sand below the sand basket.
4. The combination of a heater, its stack, a perforate sand basket having an axial space or passage that connects the heater and stack, a damper operatively mounted in 10 said passage, and a shell or casing inclosing the basket and forming therewith a surrounding hot air passage.
5. The combination of a heater, its stack, a perforate sand basket having an axial 15 space or passage that connects the heater and stack, a heat deflector in said passage, and a shell or casing inclosing the basket and forming therewith a surrounding hot air passage.
- 20 6. The combination of a heater, its stack, and a perforate sand basket having inner and outer hot air passages intermediate the heater and stack.
- 25 7. The combination of a heater, a vertically adjustable stack, and a perforate sand basket having inner and outer hot air passages intermediate the heater and stack.
8. The combination of a heater, its stack, a perforate sand basket having inner and outer hot air passages intermediate the 30 heater and stack, and means for controlling the draft through the inner passage.
9. The combination of a heater, its stack, a perforate sand basket having inner and outer hot air passages intermediate the 35 heater and stack, and a heat deflector in said inner passage.
10. The combination of a heater, its stack, a perforate sand basket having an axial space or passage that connects the heater 40 and stack, a heat deflector in said passage, bridges supporting said deflector and forming a plurality of flues or passages, and a shell or casing inclosing the basket and forming therewith a surrounding hot air 45 passage.

In testimony whereof I have hereunto signed my name in the presence of two subscribing witnesses.

THOS. N. SMITH.
